UNITED STATES PATENT OFFICE.

PETER SCIARRA, OF BENLD, ILLINOIS, ASSIGNOR TO CONADI COMPAGMICCI, OF BENLD, ILLINOIS.

CLARINET.

1,319,625.

Specification of Letters Patent.

Patented Oct. 21, 1919.

Application filed September 21, 1917. Serial No. 192,534.

To all whom it may concern:

Be it known that I, PETER SCIARRA, a citizen of the United States, residing at Benld, in the county of Macoupin and State of Illinois, have invented new and useful Improvements in Clarinets, of which the following is a specification:

This invention comprehends improvements in clarinets and has for its particular object the elimination of the difficult pass between "A" in the second space and "B" on the third line or any other pass between "A" and any other note: The way to get the "A" on the clarinet of today is to open the key with the first finger of the left hand by pressing, and then slide the finger to close the hole to get other notes. In the improved construction, I eliminate the use of the first finger for the key of "A" and use the third finger to open the key and the thumb for closing it, thus overcoming the difficulty of sliding the first finger as is necessary with the common type of clarinet.

The invention also aims to generally improve clarinets by making certain fingering more easy of accomplishment.

With these and other objects in view as will become more apparent as the description proceeds, the invention consists in certain novel features of construction, combination and arrangement of parts as will be hereinafter fully described, illustrated and claimed.

In the drawings,

Figure 1 is a front elevation of a part of clarinet constructed in accordance with my invention.

Fig. 2 is a rear elevation.

Fig. 3 is a side elevation.

Fig. 4 is a perspective view of one of the key levers and a rock shaft.

Fig. 5 is a perspective view of a lever mechanism used on the clarinet.

Figs. 6, 7 are detail views of parts to be hereinafter more fully described.

Referring in detail to the drawings by numerals, 1 designates a tube section of a clarinet having the openings 2, 3, 4 and 5. The hole 2 is provided with a cover 6 which is opened to give the note "A". This cover is fixed to an arm 7 secured to a rock shaft 8 mounted between posts 9. A finger piece 10 is formed integrally with the arm 7 and when forced toward the tube will open the cover against the action of parts to be here-

inafter fully described. A spring 11 tends to hold the cover open and to close the cover against the action of this spring, I provide a curved lever 12 secured intermediate its ends to a rock shaft 13 mounted between the posts 14. The lever 12 comprises an arm 15 which extends under the finger piece 10 and an arm 16 which is provided at its terminal with a thumb ring 17 opposed to the hole 18. A needle spring 19 fixed to one of the posts 14 by engaging a tongue 20 on the rock shaft 13 holds the arm 15 normally away from the finger piece 10.

21 designates a lever secured intermediate its ends to a rock shaft 22. The lever extends at one end over the cover 6 and overlies, adjacent its other end, a finger piece 23. This finger piece is secured adjacent one end of a rock shaft 24 mounted between posts 25, said rock shaft being provided adjacent its other end with an arm 26 to which is secured a ring 27 opposed to the hole 5. This rock shaft is pressed by a needle spring 28 secured to one of the posts 25 and normally holds the finger piece 23 elevated 75 against the lever 21.

For a clearer understanding of the improvement, other parts of the clarinet carried by the section 1 will be referred to. 29 is a cover for an opening, not shown, and 85 this cover is carried by an arm 30 which latter is secured to a rock shaft 31 mounted between posts 32. An arm 33 extends longitudinally from the fixed end of the arm 30 and is provided on its terminal with a finger 90 piece 34 which overlies a lever 35 operating a cover 36. The lever 35 is provided, as customary, with a finger piece 37. A finger piece 38 operates a cover 39 opposed to a hole, not shown. 40 is a cover secured to 95 an arm 41 and operated by an arm 42 having a finger piece 43.

The cover 6 which is normally closed, may be opened with the first finger by pressing down on the piece 23 to allow the spring 100 11 to assert itself. In this fashion, the clarinet can be operated in the old way. The cover may also be opened by rocking the shaft 24, by pressing inwardly on the ring 27 and may be closed irrespective of 105 the ring 27 by pressing the ring 17 on the lever 12 with the thumb.

While I have shown and described the preferred embodiments of my invention, it will be clearly understood that I do not 110

wish to be limited to this construction, but may make such changes as will fall within the scope and spirit of the invention as claimed.

5 What I claim is:

1. A clarinet comprising a cover, a finger piece for opening said cover, a spring engaging said finger piece to urge open said cover, a rock shaft, a curved lever connected at a point in its length with said rock shaft, said lever having one end extending under said finger piece, a ring on the other end of said lever, a spring disposed in parallelism with said shaft and engaging said lever to hold the latter normally spaced from the finger piece, said lever when operated engaging the finger piece to close said cover, a second lever having one end overlying said cover, a second rock shaft, an element projecting therefrom adjacent one end, a ring projecting from the last named rock shaft adjacent the opposite end, the element and ring extending from said shaft in a common direction, a lever pivoted intermediate its ends having its ends overlying said cover and element respectively, a resilient element carried by the last named rock shaft and of greater strength than the aforementioned spring and functioning to normally hold the latter in a position whereby the element carried thereon
- 10
- 15
- 20
- 25
- 30

gages the adjacent end of said lever, and said ring when depressed operating the shaft to lower said element and thereby permit movement of said lever and opening of 35 the cover under influence of said spring.

2. A clarinet comprising a cover, a finger piece for opening said cover, a spring engaging said finger piece to urge and hold said cover open, finger operated means disposed beneath the finger piece and operable to move the latter in a direction to close the cover, a rock shaft, an element projecting adjacent one end, a ring projecting from the rock shaft adjacent the 45 opposite end, said element and ring extending from said shaft in a common direction, a lever pivoted intermediate its ends, and having its ends overlying said cover and element respectively, a resilient element carried by the rock shaft and of greater strength than the aforementioned spring, and functioning to normally hold the latter in a position whereby the element carried thereon engages the adjacent end of said 50 lever, and said ring when depressed operating the shaft to lower said element and thereby permit movement of said lever and opening of said cover under influence of 55 said spring.

In testimony whereof I affix my signature.

PETER SCIARRA.
